H. M. M.

UNITED STATES PATENT OFFICE.

HARRY M. MAGID, OF CHICAGO, ILLINOIS.

CANOPY FOR AUTOMOBILE WINDOWS.

Application filed May 7, 1927. Serial No. 189,487.

The present invention relates particularly to awning-like shields adapted to be placed in the windows of automobiles to protect the driver or other occupants from the glare of the sun shining through such windows under certain conditions; and has for its object to produce a simple, novel, attractive and efficient device of this kind.

A further object of the present invention is to produce a device of the character described which, without the use of any tools, excepting perhaps a knife or a pair of scissors, may be fitted into a window frame of any width within limits.

15 A further object of the present invention is to produce a device of the character described that may be placed at any elevation in a window frame and be instantly adjustable into any other desired position.

20 A further object of the present invention is to produce a device of the character described that will permit a window, with which it is associated, to be almost completely closed, permitting the window opening to be 25 fully closed while the device is in position.

A further object of the present invention is to produce a device of the character described that requires no change to be made in or work to be done on a window frame to 30 which it is applied.

A further object of the present invention is to produce a simple and novel device of the character described that will not rattle in service.

35 The various features of novelty whereby my invention is characterized will hereinafter be pointed out with particularity in the claims; but, for a full understanding of my invention and of its objects and advantages, 40 reference may be had to the following detailed description taken in connection with the accompanying drawing wherein:

Figure 1 is a side elevation of a fragment of a closed automobile, showing two of my 45 improved canopies applied to windows thereof; Fig. 2 is an elevation, on an enlarged scale, of the upper portion of a door frame with the device in position thereon, parts being broken away; Fig. 3 is a section taken

50 approximately on line 3—3 of Fig. 2; Fig. 4 is a section taken on line 4—4 of Fig. 2; Fig. 5 is a section taken approximately on line 5—5 of Fig. 2, the sheet member of the canopy being omitted; and Fig. 6 is a plan view 55 of one end of the framework of the device.

Referring to the drawing, 1 represents a

window frame, such as the upper part of a door of an automobile provided with a sliding window. The frame has therein grooves 60 2 extending upwardly on the inner sides of the side members and across the underside of the top member; these grooves being the usual ones in which the window glass 3 slides.

My improved device is adapted to be inserted in the opening in the window frame 65 and, in its simplest form, consists of three elements and an adjusting nut. These three elements consist of two similar side bars or brackets 4 and 5, one of which is secured on the end of a rod 6 and the other on the end 70 of a tube 7 into which the rod is telescoped, together with the canopy proper that consists of a more or less flexible or resilient corrugated sheet 8. The rod is screw-threaded and has thereon a nut 9 adapted to abut 75 against the free end of the tube 7 to spread the side bars or brackets apart.

Each bracket consists of a bar-like member having at one end a head 10 and provided on its inner side with a groove 11 open at the 80 head end and closed at the other end. On the outer side of the head portion is a long narrow lug 12; this lug being preferably tapered so as to be more or less wedge-shaped. The parts are so proportioned that when the lugs of the two brackets are set into the groove in the window frame, at opposite sides, the nut 9 being backed off sufficiently to permit this to be done, then, upon screwing the 85 nut in the proper direction to expand the 90 cross piece, the brackets will be clamped with the bar portions inclined outwardly and downwardly from the plane of the glass in the window, the upper ends of the grooves or troughs in the brackets lying just outside 95 of the plane of the glass, that is the plane of the grooves in which the glass slides. Furthermore, the outer sides of the heads on the brackets are flat around the lugs, and of considerable area, so as to afford wide bearing surfaces between the heads and the inner surfaces of the window frame. By making the lugs tapered, they will enter window grooves of various widths without being loose 100 therein and rattling.

105 The canopy proper may be made of celluloid or rubber, or any suitable material, and it is corrugated along longitudinal lines so that its normal overall thickness is somewhat greater than the width of the grooves 11 in the brackets. Therefore, when the canopy is forced into the grooves in the brackets, it is

held in place with a frictional pressure. The member 8 is adapted to be inserted into the brackets through the open ends of the grooves or slots, and it is somewhat wider than the length of the brackets so that, as shown in Figs. 2, 3 and 4, a marginal portion projects beyond the upper ends of the brackets and into the top portion of the groove in the window frame when the device is positioned in the top of the window opening. Therefore, when my improved device is mounted in the extreme upper portion of the window opening, the upper part of the same makes a closed joint with the window frame and prevents the entrance of wind or rain.

In the underside of each of the bracket heads is a notch 14 into which the upper edge of the window glass may extend when the window is pushed up.

If desired, a wing screw 15 may be applied to the nut 9, on the inner side of the window, to prevent rotation of the nut and theft of the canopy device when the automobile is closed and locked.

It will be seen that the same device can be fitted into windows of various widths; the corrugated sheet member of the canopy being made long enough to fit a wide window, and being simply cut to the proper length with a knife or scissors when the device is to be applied to a narrower window. The cross piece between the brackets, consisting of the rod and the tube, is of course adjustable to any desired length through the mere turning of the knurled nut 9. Therefore the device may be applied to a window of any width, without mutilating or in any way changing the window frame or adding to the latter anything that is not removed through the mere act of backing up the nut 9; no tools of any kind being required. It will furthermore be seen that the device may be placed at any desired elevation in a window opening, being adapted to be quickly and easily adjusted from one position to another and locked in its new position. Furthermore, when the device is placed in the top of a window opening, it permits the window to be almost completely closed, leaving only enough opening to afford ventilation, but definitely preventing the entrance of wind or rain.

While I have illustrated and described with particularly only a single preferred form of my invention, I do not desire to be limited to the exact structural details thus illustrated and described; but intend to cover all forms and arrangements which come within the definitions of my invention constituting the appended claims.

I claim:

1. A device of the character described comprising a holder adapted to extend across and be frictionally held in a window frame, said

holder having grooves adapted to lie at opposite sides of the window opening and facing each other in a plane forming an angle with the plane of the window, said grooves being open at the ends that are the inner ends when the device is on a window, and a stiff canopy sheet of a length sufficient to extend between said grooves, said sheet being adapted to be slipped into the grooves through their open ends. 70

2. A device of the character described comprising a holder adapted to extend across and be frictionally held in a window frame, said holder having grooves adapted to lie at opposite sides of the window opening and facing each other in a plane forming an angle with the plane of the window, and a canopy sheet adapted to be engaged at its ends in said grooves said sheet being of resilient material and being corrugated, and the normal overall thickness of the sheet being somewhat greater than the width of the grooves. 80

3. A structure of the character described comprising a holder having parallel grooves spaced apart and facing each other, the grooves being open at corresponding ends and closed at the other ends, and a sheet of resilient material long enough to extend between said grooves and corrugated at its ends so as to have a normal overall thickness somewhat greater than the width of the grooves. 90

4. A device of the character described comprising two brackets, a lengthwise adjustable spreader between said brackets, the brackets having on their inner sides grooves facing each other, and a long sheet of resilient material corrugated along longitudinal lines and of a greater overall thickness to permit it to be readily cut to a desired length. 100

5. A device of the character described comprising two brackets having on their outer sides lugs to engage grooves in a window frame and on their inner sides longitudinal grooves opening out of one end thereof and closed at the other end, an adjustable spreader between said brackets, and a canopy sheet adapted to extend between said brackets and fit at its ends into said grooves. 110

6. A device of the character described comprising two brackets having on their outer sides lugs to engage grooves in a window frame and on their inner sides longitudinal grooves opening out of one end thereof and closed at the other end, an adjustable spreader between said brackets, and a canopy sheet adapted to extend between said brackets and fit at its ends into said grooves, said sheet being somewhat wider than the length of said grooves so as to project beyond the brackets at the open ends of the grooves. 115

7. A device of the character described comprising two brackets having lugs to engage grooves in a window frame, said lugs decreasing in thickness from the inner toward their outer ends so as to permit them to fit grooves 130

of various widths, and a canopy sheet adapted to extend between said brackets.

8. A device of the character described comprising two brackets, a rod fixed to one end of one of the brackets and extending at right angles thereto, a tubular member fixed to one end of the other bracket and extending at right angles thereto and having an internal diameter large enough to permit said rod to enter, said rod being screwthreaded at its free end and having thereon a nut adapted to engage the free end of said tubular member, said brackets having on their inner sides grooves facing each other and lying in a plane parallel to but above said rod and tube, said grooves being open at the supported ends of the brackets, and a canopy sheet adapted to be inserted into said grooves through their open ends.

10 9. A device of the character described comprising two brackets, an adjustable spreading device between one end of each bracket and the corresponding end of the other bracket, the ends of the brackets at which 15 the spreader is located being shaped to fit into the top of the opening in a window frame and rigidly hold the brackets projected outwardly at an angle to the vertical, said brackets having grooves extending lengthwise thereof in the sides facing each other, and a canopy sheet having its edges engaged in said grooves and having a free end projecting beyond said brackets to engage with the top of the window frame.

35 10. A device of the character described comprising a canopy adjustable as to its width, an adjustable spreader arranged at one end of the canopy and adapted to spread the latter and lock the canopy in frictional engagement with the sides of a window frame and downwardly inclined position.

40 11. A device of the character described comprising a canopy adjustable as to its width, an adjustable spreader arranged at one end of the canopy and adapted to spread the latter and lock the canopy in frictional engagement with the sides of a window frame

and hold the canopy in an outwardly and downwardly inclined position said canopy 50 being constructed with the top of a frame and with the top of a window in said frame and a closure for the frame opening when the window is closed.

12. A device of the character described 55 comprising two brackets, a spreader between corresponding ends of said brackets, and a canopy sheet extending between said brackets, each bracket having at the spreader end an element adapted to engage with the adjacent side of a window frame in which the device is placed to lock the canopy in an outwardly and downwardly inclined position with respect to the frame when said spreader is adjusted to press said elements into close 60 65 contact with the frame.

13. A device of the character described comprising two brackets having on their outer sides at one end elements to engage with the adjacent inner sides of a window 70 frame in which the device is placed, said brackets having on their inner sides longitudinal grooves opening out of said ends of the brackets, and a canopy sheet adapted to extend between said brackets and fit at its 75 ends into said grooves, the sheet and the brackets being constructed and arranged to cause the sheet to be tightly held in said grooves.

14. A device of the character described 80 comprising two brackets, an adjustable spreader between corresponding ends of said brackets, said brackets having in the sides directed toward each other longitudinal grooves, a canopy of resilient sheet material 85 corrugated along longitudinal lines, the overall thickness of the canopy being slightly greater than the width of the grooves, whereby the canopy may be cut off to the proper length to fit and be frictionally held 90 in the grooves when the spreader is adjusted to bring the brackets nearer together than the original length of the canopy.

In testimony whereof, I sign this specification.

HARRY M. MAGID.
